US00D918930S

(12) **United States Design Patent** (10) **Patent No.:** **US D918,930 S**
Dill et al. (45) **Date of Patent:** **** May 11, 2021**

(54) **DISPLAY SCREEN OR PORTION THEREOF
WITH A GRAPHICAL USER INTERFACE**

(71) Applicant: **Lyft, Inc.**, San Francisco, CA (US)

(72) Inventors: **Katherine Marisa Dill**, San Francisco, CA (US); **Gordon Tindall**, San Francisco, CA (US); **David Bellona**, San Francisco, CA (US); **Karina van Schaardenburg**, San Francisco, CA (US); **Timothy Johnson**, Brooklyn, NY (US); **Jeffrey Hurray**, San Francisco, CA (US); **Linda Dong**, San Francisco, CA (US); **Kai Xiao Fang**, New York City, NY (US); **Benjamin Lee**, San Francisco, CA (US)

(73) Assignee: **LYFT, INC.**, San Francisco, CA (US)

(**) Term: **15 Years**

(21) Appl. No.: **29/650,444**

(22) Filed: **Jun. 6, 2018**

(51) **LOC (13) Cl.** **14-04**

(52) **U.S. Cl.**

USPC **D14/485**

(57) **CLAIM**

The ornamental design for a display screen or portion thereof with a graphical user interface, as shown and described.

DESCRIPTION

The FIGURE is a front view of a display screen or portion thereof with a graphical user interface showing our new design.

The broken-line rectangle at the periphery of the FIGURE illustrates a display screen or portion thereof and forms no part of the claimed design. The remaining broken lines show portions of the graphical user interface and form no part of the claimed design.

1 Claim, 1 Drawing Sheet
